UNITED STATES PATENT OFFICE.

PAUL LENGEMANN, OF BREMEN, GERMANY.

FOOT-ARCH SUPPORT.

Application filed January 26, 1926, Serial No. 83,795, and in Germany March 16, 1925.

This invention relates to a foot-arch support and consists in the provision of a resili-
ent comb-shaped metal plate whose teeth are
arranged so as to bear against the arch at the
inside of the foot only, the teeth being sepa-
rated by spaces of about the same width as
the teeth themselves for convenient insertion
of temporary nails or brads for connecting
the shoe upper, welt and sole together.

10 The invention is illustrated in the accom-
panying drawing, which is a bottom plan
view of the shoe with the out sole removed.

15 The foot-arch support consists of a resili-
ent metal plate *b* presenting a comb-shaped
structure. The body of the plate is perma-
nently connected near its center to the insole
of the footwear *a* as it is built up in any suit-
able manner, for instance, by means of nails
or screws *c*. The approximately parallel ar-
20 ranged teeth *d* of the comb extending to one
side of said body portion and integral therewith
are formed so as to support the arch at
the inside of the foot only, and they are
separated by spaces of about the same width
25 as the teeth themselves.

The spacing of the teeth gives the latter

full freedom of movement and renders the
support highly resilient and exceedingly
comfortable.

In the case of a welt shoe, the outsole is 30
stitched to the welt except where the teeth *d*
interfere. Then the outsole is either tacked
or stitched to the welt between the teeth.

In the case of a McKay shoe, the outsole is
either stitched or nailed to the insole, as in 35
a usual McKay shoe, except where the teeth
d interfere. Then the outsole is nailed to the
insole between the teeth.

I claim:

A shoe having incorporated therein a me- 40
talic arch support comprising a body portion
permanently secured to the insole and pro-
vided on its inner side with a plurality of
approximately equally spaced and parallel
narrow, resilient, integral teeth, said teeth 45
extending from between the outsole and in-
sole against the upper of the shoe to support
the arch of the foot, and the spaces between
the teeth being of sufficient width to allow
securing means to be passed through said 50
spaces.

PAUL LENGEMANN.
